UNITED STATES PATENT OFFICE.

FRANCISCO L. GODINEZ, OF JERSEY CITY, NEW JERSEY, AND ALBERT J. MARSHALL, OF NEW YORK, N. Y., ASSIGNEES TO GODINEZ-MARSHALL COMPANY, OF NEW YORK, N. Y., A CORPORATION OF NEW YORK.

LAMP.

1,019,246.

Specification of Letters Patent.

Patented Mar. 5, 1912.

Application filed October 17, 1911. Serial No. 655,190.

To all whom it may concern:

Be it known that we, FRANCISCO L. GODINEZ and ALBERT J. MARSHALL, citizens of the United States, and residents of Jersey City, 5 Hudson county, New Jersey, and borough of Manhattan, city, county, and State of New York, respectively, have invented certain new and useful Improvements in Lamps, of which the following is a specification.

10 This invention relates to what are ordinarily termed "portable lamps". It has been our purpose to make such a device of neat and attractive appearance and one which will more perfectly and uniformly 15 diffuse the rays of light from the lamp.

Another object is to selectively control the color of the rays emitted by the lamp.

The novel features of the invention will be apparent from the following description 20 taken in connection with the drawings.

In the drawings, Figure 1 shows a side view partly in section of a lamp embodying our invention; and Fig. 2 is a perspective view of some of the parts of our device.

25 As will be seen by reference to Fig. 1 we make use of a base pedestal 1 which may be of any desired ornamental form, and it will be understood that the electric wires for supplying current to the lamp enter in the usual way at 2. At the top of the pedestal 1 there is an ordinary socket for an electric incandescent light and surrounding this socket, a part of the upper end of the pedestal, there is a holder 3 which may be made of ornamental form. Its lower end 4 fits on and is secured to the pedestal while its upper end 5 is made ring-like with an interior supporting flange. Screws 6 pass through the said holder near its upper edge for the purpose

40 of engaging a bead 7 at the bottom of the bell-shaped dome 8. The holder 3 may give an ornamental appearance and it will conceal from view the socket of the incandescent lamp or other light producing means. The

45 dome 8 is made of glass and is in the shape of an inverted bell which may be hemispherical as shown. It may be made of prismatic glass or any other translucent form which permits light to pass through it. A 50 frame 9 having a circular base 10 with a depending end flange fits on the upper circular rim 11 of the dome 8 and the flange fitting down in this dome securely holds the frame in position. The frame has at its top a plate

12 provided with a central projection 13 55 extending upwardly and there is a central hole through this projection and plate. The shade 14, in the shape of a dome, which may be made of cut glass or other ornamental material, fits over the plate 12 and has a central opening 15 through which the projection 13 extends. A clamping plate or member 16 fits down on top of the projection 13 and extends out over a portion of the shade to clamp it in position, and this plate has a 60 screw-threaded stem 17 extending down through the opening in the projection 13 where it is engaged by a nut 18 to hold it in position.

It will be observed that by the above construction the incandescent lamp 19 is surrounded by the translucent dome 8 and the light from this lamp is diffused uniformly around the device and it is not interrupted by the opaque supporting means for the 75 shade. The frame which supports the shade rests on top of the glass bell-shaped dome and is out of view, not interfering in any way with the transmission of the light to the points where it is desired to be used. 80

In the bottom part of the column or pedestal 1 there is mounted a device 20 for selectively controlling the color of the rays emitted by the light source. This device is in the shape of an arm which moves in the 85 slot 21 to different positions and in moving it regulates the resistance in the circuit leading to the lamp, and we have found that this results in changing the color effect of the light. 90

Having thus described our invention what we claim and desire to secure by Letters Patent is:

1. In a lamp, the combination with a base, of a translucent inverted bell-shaped 95 dome thereon adapted to contain a light, and a shade supported from and surrounding the upper edge of said dome.

2. In a device of the class described, the combination with a pedestal adapted to 100 carry a lighting element at its top, of a translucent bell-shaped dome secured thereto surrounding said lighting element and extending upwardly from said pedestal, and a shade carried by and surrounding 105 said bell-shaped dome and spaced therefrom.

3. In a device of the class described, the combination with a pedestal, of light pro-

ducing means carried on the upper end of said pedestal, a shade, and means extending upwardly from said pedestal around said light producing means for supporting 5 said shade, the lower edge of the shade surrounding the supporting means, the said supporting means being translucent whereby the light will be uniformly diffused.

4. In a device of the class described, the 10 combination with a pedestal, of light producing means carried on the upper end of said pedestal, a shade, an inverted translucent bell-shaped dome secured to the top of said pedestal and extending up around 15 said light producing means, and means independent of the dome for supporting said shade from the upper edge of said bell-shaped dome.

5. In a dome of the class described, the 20 combination with a pedestal adapted to carry a lighting element at its top, of a hemispherical transparent dome secured to the upper end of said pedestal and extending upwardly around said lighting element, 25 a frame resting upon the upper edge of said dome, and a shade carried by said frame and surrounding the same.

6. In a dome of the class described, the 30 combination with a pedestal adapted to carry a lighting element at its top, of a hemispherical transparent dome secured to the upper end of said pedestal and extending upwardly around said lighting element, a frame having a ring-like base resting

upon the upper edge of said transparent 35 dome, a shade adapted to fit over said frame, and means at the top of said frame for clamping and securing said shade thereon.

7. In a device of the class described, the 40 combination with a pedestal adapted to carry a lighting element at its top, of a prismatic hemisphere secured to said pedestal surrounding said lighting element, a frame mounted on said hemisphere, and a dome secured on said frame and depending 45 therefrom around said hemisphere.

8. In a device of the class described, the 50 combination with a pedestal, of a lamp socket at its top, a holder surrounding said socket forming a part of said pedestal, a translucent hemisphere secured in said holder and extending upwardly therefrom, a frame having a ring-like base resting on the top of said hemisphere and having a central upwardly extending projection at 55 the top, a dome having a central opening fitting on said projection, and a clamping member secured to said projection and extending over a portion of the dome to clamp it in place.

In testimony whereof we affix our signatures in presence of two witnesses.

FRANCISCO L. GODINEZ.
ALBERT J. MARSHALL.
